(57) **CLAIM**

The ornamental design for an electrical connector, as shown and described.

DESCRIPTION

FIG. 1 is a top, front, left-side perspective view of an electrical connector embodying our design;

FIG. 2 is a top, rear, right-side perspective view thereof;

FIG. 3 is another front, left-side perspective view thereof;

FIG. 4 is another rear, right-side perspective view thereof;

FIG. 5 is a front elevation view thereof;

FIG. 6 is a rear elevation view thereof;

FIG. 7 is a left-side elevation view thereof;

FIG. 8 is a right-side elevation view thereof;

FIG. 9 is a top plan view thereof; and,

FIG. 10 is a bottom plan view thereof.

The broken lines present in the drawings illustrate portions of the article which form no part of the claimed design.

1 Claim, 10 Drawing Sheets
